Primary Examiner — Mary Ann Calabrese

Assistant Examiner — Hillary Catherine Shepard

(57) **CLAIM**

The ornamental design for a metal vertical filing cabinet, as shown and described.

DESCRIPTION

FIG. 1 is a front, top, and right perspective view of a metal vertical filing cabinet, showing my new design;

FIG. 2 is a bottom, rear, and left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 2; and, FIG. 10 is an enlarged detail view of area 10 in FIG. 3.

The broken lines in the drawings illustrate the portions of the metal vertical filing cabinet, which form no part of the claimed design.

1 Claim, 10 Drawing Sheets
